The ornamental design for a video cassette recorder, as shown and described.

DESCRIPTION

FIG. 1 is a top, front, and right side perspective view of a video cassette recorder showing my new design;

FIG. 2 is a top, front, and right side perspective view thereof showing a front cover in the open position;

FIG. 3 is a top plan view thereof;

FIG. 4 is a front elevational view thereof;

FIG. 5 is a rear elevational view thereof;

FIG. 6 is a bottom plan view thereof; and

FIG. 7 is a right side elevational view thereof, the left side being a mirror image.
